W. J. CAHILL

HORSESHOE

Original Filed July 28, 1922

UNITED STATES PATENT OFFICE.

WILLIAM J. CAHILL, OF NEW YORK, N. Y.

HORSESHOE.

Application filed July 28, 1922, Serial No. 578,105. Renewed April 11, 1924.

To all whom it may concern:

Be it known that I, WILLIAM J. CAHILL, a citizen of the United States, and a resident of the city of New York, borough of Richmond, Great Kills, in the county of Richmond and State of New York, have invented a new and Improved Horseshoe, of which the following is a full, clear, and exact description.

10 This invention relates to a horseshoe, and has particular reference to various improvements in a horseshoe whereby it is capable of a variety of uses.

An object of the invention is to provide a 15 simple, efficient, strong, durable shoe provided with a removable combined toe calk and clip.

Another object resides in the provision of 20 means whereby the shoe is easily and simply provided with a removable plate to be disposed across the shoe beneath the foot of the horse or other animal, to prevent the foot from being clogged with stones and dirt.

Another object resides in the provision of 25 means whereby the shoe is not nailed all the way back to the heel, so that not only is this portion of the shoe free to move but the hoof of the horse's foot at this point can be cut down shorter than the general practice so 30 that the frog or pad of the horse's foot will come in contact with the ground first and thereby ease the blow for the horse. The use of the hereinafter described removable toe calk and clip eliminates the necessity for 35 nailing the heel, since any tendency for the shoe to slip is prevented.

A further object resides in the provision of means whereby this removable plate can be very readily and firmly fastened onto the 40 shoe.

A still further object resides in the provision of means whereby the means for fastening the plate and the means for fastening a removable toe piece are identical.

45 Another object resides in the particular construction and arrangement of parts which are hereinafter described and claimed and shown in the accompanying drawings.

The invention is illustrated in the drawings, of which—

50 Figure 1 is an inverted plan view of the shoe,

Fig. 2 is a plan view,

Fig. 3 is a front elevation,

Fig. 4 is a section taken on the line 4—4 of 55 Fig. 1,

Fig. 5 is a section taken on the line 5—5 of Fig. 1,

Fig. 6 is a section taken on the line 6—6 of Fig. 1,

Fig. 7 is a perspective of the combined toe 60 calk and clip, and

Fig. 8 is a section similar to Fig. 4 through a modified form of shoe.

The forms of the invention shown in the 65 drawings are preferred forms, although it is understood that modifications in the construction and arrangement of the parts and in the character of the materials used may be adopted without departing from the 70 spirit of the invention.

The invention includes a horseshoe 1 of 75 ordinary shape having the usual narrow gripping plates 2 disposed on the lower face along the quarters of the shoe, and also with heel calks 3 which, as shown in Fig. 6, are spaced slightly apart from the heels of the shoe proper to permit the insertion therebetween of a device hereinafter to be described.

At the front or toe the shoe is 80 cut away to receive a removable toe piece 4 having a toe clip 5 integrally disposed thereon and extending upwardly from the shoe, and a toe calk 6 integrally formed on the plate and extending downwardly therefrom. As shown in Fig. 7, this removable toe piece or plate is provided with a portion 7 extending rearwardly therefrom and provided with an aperture through which a 85 suitable bolt passes. Adjacent the portion 7 are two rearwardly extending ears 8 adapted to lie against the under face of the forward portion of the shoe and spaced apart from the portion 7 so that to fit the varying curvatures of different kinds of shoes the plate 4 may be bent without causing the

95

portions 7 and 8 to conflict with each other. By reason of the fact that this plate is removable, and in a very simple manner, the toe calks and clips can be removed at any time whenever it is desired to relieve the horse's foot from the pressure and confining influence of the toe clip without otherwise affecting the disposition of the shoe on the foot.

10 In order also to provide means whereby stones and dirt will not collect in the usual manner in the hollow portion of a horse's foot, between the edges and the frog of the foot, and tend to injure the horse, I have provided a removable plate 9 made of any suitable material, of which some light metal such as aluminum is an example; and this plate is shaped to conform to the opening between the parts of the shoe, as shown in Fig. 4, by providing a depressed portion 14 simulating the shape of the frog of the foot. This plate 9 has attached thereto at the rear end thereof, a crossbar 10 having end portions adapted to lie in the space between the heels 3 and the ends of the shoe. These end portions 11 abut the ends of the gripping plates 2 and are firmly spaced on the shoe by reason of these engagements. The forward end of the plate is provided with an extension 12 having an aperture through which a bolt or other device 13 passes. This device 13, which may be a set-screw, engages in an aperture in the front end of the shoe and holds the front end of the plate 9 firmly thereagainst. This set-screw or fastening means also passes through the aperture in the portion 7 in the toe plate so that this single means will hold the plate 9 and the toe plate 4 on the shoe. To remove these plates, it is merely necessary to loosen the bolts 13, whereupon the plate 9 and the toe plate 4 can be taken out both together or either one separately.

With regard to the use of the plate 9, it is often found, especially with racing horses, that in practice they often lame themselves by picking up stones and having their feet become clogged with clay, but by having this plate on the shoe this tendency to become lame is eliminated. By being made of some light material, the plate will not seriously affect the running of the horse. I also prefer to provide the plate, as shown in Fig. 1, with a depressed portion 14 stamped out in the form of the frog of the horse's foot, so that the frog will fit snugly or neatly therein without undue pressure being exerted thereon. On the inner face of the plate I generally provide a layer of some soft material 15, such as felt, which will cushion the pressure of the plate and shoe on the horse's hoof.

As shown in Fig. 8, I have provided a plate 9^a which is flat, instead of having a

depressed portion, and is provided with a layer 16 of some suitable cushioning material.

I have, therefore, provided a simple and efficient horseshoe having attachments which enable it to be used under many circumstances to provide a comfortable shoe for the horse, and one which will enable the horse to be handled with the highest degree of efficiency with regard to the condition of his feet so that he will not be subject to the usual troubles which are caused by the poor condition of a horse's feet.

What I claim is:

1. A horseshoe which includes a plate disposed across between the parts of the shoe to cover the open space formed therebetween, a removable toe piece, means for fastening the toe piece to the shoe, and means on the plate to engage with the first-mentioned means whereby the same means will hold the toe piece and plate to the shoe. 80

2. A horseshoe which includes a plate disposed across between the parts of the shoe to cover the open space formed therebetween, a removable toe piece, means for fastening the toe piece to the shoe, means on the plate to engage with the first-mentioned means whereby the same means will hold the toe piece and plate to the shoe, and means formed on the heel of the shoe to engage 95 the other end of the plate to hold it in position.

3. A horseshoe which includes a removable toe piece, a toe clip extending upwardly from a portion thereof, a toe calk extending in the opposite direction from the same portion, a portion extending rearwardly from the toe piece having an aperture therein to receive a set-screw or bolt to fasten the toe piece to the shoe, and a pair of rearwardly extending ears on the ends of the toe piece on opposite sides of said portion, said ears adapted to assist in the disposal of the toe piece on the shoe, said ears spaced apart from the above-mentioned portion to permit the toe piece to be bent to conform to different shapes of shoes. 100

4. A horseshoe which includes turned-over heel calks spaced apart from the heel to form a space therebetween, a plate disposed across the shoe to cover the opening therein, and a bar at the rear end of said plate having end portions extending into the space between the heel calks and the heels of the shoe to align the plate properly on the 115 shoe. 120

5. A horseshoe which includes turned-over heel calks spaced apart from the heel to form a space therebetween, a plate disposed across the shoe to cover the opening therein, a bar at the rear end of said plate having end portions extending into the space between the heel calks and the heels of the 125 shoe.

shoe to aline the plate properly on the shoe, and a pair of gripping plates disposed along the underface of the shoe, said plates having shoulders against which the ends of said bar rest to limit the movement of the bar.

6. A horseshoe which includes turned-over heel calks spaced apart from the heel to form a space therebetween, a plate disposed across the shoe to cover the opening 10 therein, a bar at the rear end of said plate having end portions extending into the space between the heel calks and the heels of the

shoe to aline the plate properly on the shoe, a pair of gripping plates disposed along the under face of the shoe, said plates having 15 shoulders against which the ends of said bar rest to limit the movement of the bar, an extension on the forward end of said plate having an aperture therein, said shoe having an aperture to be alined with said first- 20 mentioned aperture, and a bolt to pass through said apertures to hold the plate to the shoe.

WILLIAM J. CAHILL.
